MICROSCOPE

John T. Armbruster, Niagara Falls, N.Y., assignor to
American Optical Company, Southbridge, Mass.

Filed Nov. 27, 1962, Ser. No. 72,623

Term of patent 14 years

(Cl. D57—1)

FIGURE 1 is a front perspective view of a microscope showing my new design;

FIGURE 2 is a rear elevation thereof with portions omitted for convenience of illustration; and

FIGURE 3 is a top plan view thereof as shown in FIG. 2.

The appearance of my microscope is substantially the same when viewed from either side thereof.

The dominant features of my design reside in the portions shown in full lines.

I claim:

The ornamental design for a microscope, as shown and described.
